PAPER CONTAINER.

Application filed November 7, 1919. Serial No. 336,292.

The present invention relates to paper containers, that is to containers made of any suitable fibrous stock whether paper or resembling paper, and particularly to the 5 neck, bottom and closures therefor. The container may be in the form of a can with a cylindrical side wall, or in any polygonal or curved form, but preferably in the form of a firkin with a tapering side wall. The 10 paper stock of which the container is constructed may be single ply or multiple ply with or without incorporating a binder.

The paper stock used in the container is, prior to formation, more or less porous, and 15 therefore subject to expansion and contraction due to varying temperature and humidity. I have found that under compression of from 6,000 to 10,000 pounds per square inch, the stock becomes highly 20 compressed and practically solidified so as to be substantially unchangeable in dimensions by moisture or heat. Also I have found that the portions of the stock folded under such pressure may, under certain conditions, 25 unite, cohere, become welded together or consolidate with each other along the meeting surfaces. For instance, if stock is used, which is practically non-calendered, the fibers at the meeting surfaces meet or inter- 30 lace somewhat as they do in the structure of the paper stock itself, so that a practically integral formation at these points is produced. This is true especially when the stock is made more pliable by heating, so 35 that not only does the finished container remain substantially unaffected by varying atmospheric conditions, and therefore maintains its gage dimensions, but the folded portions resist separation along their meeting 40 surfaces to an extent depending upon the texture of the stock, but in some cases as much as the body itself of the folded portions. The use of asphaltum or adhesive material as a binder, heated by the dies or 45 otherwise in forming the container, increases the degree of solidification even when the binder originally exists between the plies of the paper stock and not on either surface of the multiple-ply stock. When semi-calendered 50 stock is used without a binder, the meeting surfaces of the stock may be more readily separated by force, but with a binder a greater degree of resistance to separation is present. Whether or not the folded 55 portions are consolidated, or merely brought

into intimate surface contact, I have found that as a result of the highly-compressed and practically-solidified condition of the folded portions resulting from the great pressure used in forming the container, and 60 also as a result of the forms of construction hereinafter described, the container, and particularly the neck, bottom and closures thereof, take a rigid set impenetrable to moisture and liquids, and permanently 65 maintained at gage dimensions under normal atmospheric conditions.

Irrespective of the form of the container and the bottom closure therefor, the invention comprehends as one of its parts a paper 70 container with a reenforced neck, preferably double-reenforced, formed from a continuation of the stock of the side wall and folded under great pressure into rigidly set portions in intimate surface contact, which portions may or may not be united or consolidated depending principally upon the surface finish of the stock and whether or not a binder is used. Preferably, the meeting edges of the side wall and the folded 75 neck portions are rigidly set in intimate surface contact, with or without being consolidated, and the neck has a flat periphery without a joint so that the tendency to separate or collect foreign matter at the 80 junction of the side wall and neck is reduced in a container that is nicely finished off.

In the specific embodiment hereinafter described, the neck is double-reenforced comprising a base portion continuing from the side wall, an intermediate portion reversely extending inside the container, and a terminal portion enclosed within the other portions, the joining section of the base and intermediate portions lying flat over the periphery of the terminal portion, and the joining section of the intermediate and terminal portions lying in uninterrupted conformity with the inside face of the side wall. 90 Where the neck has a cap-retaining groove, it is advantageous to have the intermediate portion extend inside the container, because the upper and lower peripheral edges of the 95 groove are then better adapted to tightly grip a cap seated therein, particularly where the upper peripheral edge thereof lies outside the lower peripheral edge to form an extended bearing surface against which the cap is tightly seated and prevented from en- 100 105 110

tering the container further. In that case, I prefer further to flare the neck outwardly from the side wall, so that the cap is guided into the groove. Where the neck is reenforced and solidified to give a sufficient body of stock rigidly set, the cap is tightly retained in the groove although removal therefrom at will.

The invention comprehends as another of its parts a permanent closure at either or both ends of a paper container of any suitable form wherein a paper member may have a folded base portion with a reversely-extending terminal portion of abbreviated length, the continuing portion of the side wall of the container preferably being consolidated or rigidly set in intimate surface contact with the inside and outside surfaces of the base and terminal portions to form a hermetically-sealed interlocked joint. The closure may have a flat outer periphery on which to stand, of a width totaling a double thickness of the member and a triple thickness of the side wall continuing portion. Furthermore, the closure may have a flat inner periphery preferably in consolidation or rigidly set in intimate surface contact with said member to support its periphery, and an intermediate ledge folded over the periphery of the terminal portion and preferably in consolidation or rigidly set in intimate surface contact therewith, to further ensure the permanency of the closure.

A paper container having a reenforced neck of the kind hereinbefore described, and a hermetically-sealed bottom closure of the kind hereinbefore described, is suitable for a can or firkin for transporting and storing liquids or solids. Whereas the side wall is comparatively thin, and therefore economical of stock, the reenforced neck and the interlocked bottom closure furnish a sufficiently thick body of stock on which to work under the great pressure required to cause practical solidification, or cohesion of the layers of the stock, whether of single or multiple ply with or without a binder, and to consolidate or rigidly set the folded portions in intimate surface contact maintaining their gage dimensions after forming. Thus, not only are the parts impenetrable to moisture, liquids and solids, but when tapered they nest perfectly, and when capped after filling they invariably produce a tightly sealed container.

In the accompanying drawings illustrating the preferred form of my invention in application, as an example, to containers having a tapering side wall with a permanently-sealed bottom closure and a removable cap in a cap-retaining groove of a multi-reenforced neck, wherein the folded portions of the bottom closure and neck are consolidated.

Fig. 1 is an elevation, partly in section,

of a container of single-ply stock, with a fragment of the cap in place; Fig. 2 is an enlarged detail of the double-reenforced neck thereof; Fig. 3 is an enlarged detail of the permanently-sealed bottom closure thereof; Fig. 4 is an enlarged detail of the double reenforced neck formed of two-ply stock incorporating a binder; and Fig. 5 is an enlarged detail of a permanently-sealed bottom closure therefor formed of two-ply stock in the side wall and in the bottom, both incorporating a binder.

In both embodiments, the container has a tapering side wall 1 of non-calendered stock, a double-reenforced neck 2, and a permanently sealed bottom closure 3, all circular in cross section.

Referring to the embodiment of Figs. 1, 2 and 3, the double-reenforced neck is formed of a base portion 4 continuing from the side wall 1, an intermediate portion 5 reversely extending inside the container, and a terminal portion 6 enclosed between the other two portions, the base and intermediate portions having a joining section 7 with a flat periphery, and the joining section 8 between the intermediate and terminal portions lying in smooth conformity with the inside surface of the side wall. The neck has a cap-retaining groove 9 bounded below by the joining section 8 and bounded above by the upwardly flaring section 10 having an angle of taper greater than that of the side wall 1. A paper cap 11, in the form of a disc and of suitable stock, is retained in the groove 9.

I have found that the great pressure which a multi-reenforced neck of this kind is capable of withstanding in being formed by spinning or compression, is sufficient to consolidate the turned-over portions by forcing the fibers thereof into intimate meeting or interlacing, and thereby produce such a solid formation as to rigidly set and retain the neck at gage dimensions, that is, at the dimensions at which it is originally formed. Furthermore, the consolidation produced at 12, where the side wall 1 meets the joining section 8, precludes the entry of moisture, liquids, or solids between the folded portions, whereas the consolidation produced between the section 7 and the periphery of the terminal portion 6 precludes capillary action through the paper stock of the neck.

It will be observed that the diameter of the upper peripheral edge of the cap-retaining groove 9 is greater than that of the lower peripheral edge, or lies outside it. Accordingly, not only does the cap 11 have an extended bearing surface at 13, but, as a result of the resiliency of the neck 2, due in part to its multi-reenforcement of consolidated portions and the resulting retention of its gage dimensions, the cap, which inherently retains its diameter, is pressed so

tightly along the upper peripheral edge of the groove that a tight seal is obtained between the neck and the cap. However, the cap may be removed at will by pulling up its center or prying between its periphery and the groove. Furthermore, the flaring section 10 assists in guiding the cap into the groove 9, whereas the lesser diameter of the lower peripheral edge of the groove ordinarily prevents the cap from being forced further into the container.

The bottom closure of the container is formed by interlocking the continuing portion of the side wall 1 with a bottom member 14 of non-calendered stock. In this closure, the base portion 15 and the terminal portion 16 of the abbreviated length are enclosed along their inside and outside surfaces by the continuing portions 17, 18, 19 of the side wall, the closure having a flat outer periphery at 20 of a width totaling three thicknesses of the side wall and two thicknesses of the bottom member. A flat inner periphery at 21 supports the bottom member 14 around the periphery thereof and acts to hold the bottom member at the side wall. The intermediate ledge 22 covers the periphery of the terminal portion 16, while the joining section 23 of the base and terminal portions of the bottom member covers the periphery of the downwardly-extending portion 19.

I have found that the great pressure which an interlocked joint of this kind is capable of withstanding in being formed by spinning or compression, is sufficient to consolidate the folded portions and to rigidly set and retain the bottom closure at gage dimensions. Furthermore, the impenetrability of the closure, and the solid formation thereof, serve to preserve a hermetical closure against the egress of the contents of the container and against the ingress of air, moisture, liquids or solids from the outside. The closure is further enhanced by the consolidation existing between the inner periphery at 21 and the bottom member 14, while the consolidation of the intermediate ledge 22 with the periphery of the terminal portion 16, and the consolidation between the joining section 23 with the periphery of the portion 19 preclude capillary action through the paper stock of the interlocked portions.

The embodiment shown in Figs. 4 and 5 is similar to that of the preceding embodiment excepting that the side wall is made of two-ply non-calendered paper stock 24, 25 incorporating a binder 26 of asphaltum or adhesive. Likewise the bottom member is paper of two-ply non-calendered stock 27, 28 incorporating a binder 29 of asphaltum or adhesive. In applying pressure by dies, which are preferably heated to about 200° F., the multi-reinforced neck and the inter-

locked bottom closure are solidified to a greater degree with the two-ply stock incorporating a binder, than is the case with the single-ply stock of the first embodiment, so that the container assumes an increased rigidity of set, more tightly clamping the neck in a hermetical seal with the cap 11 seated in the groove 9, and more solidly compacting the bottom closure in the interlocked joint. Furthermore, the folded portions of the neck and bottom are consolidated to a greater degree.

Whether of single-ply or multiple-ply stock, the container herein described is particularly suitable for nesting for transportation, the caps, of course, being removed. The smooth inside and outside surfaces of the container between the neck 2 and the bottom member 4, together with the uninterrupted conformity existing between the inside surface of the side wall 1 and the joining section 8, assist materially in reducing the hazard of damage in nesting and separating the containers, and increase the number of containers capable of being nested in a given length. The substantial permanency of the gage dimensions of the side wall, neck and bottom closure of the containers, due to the herein described character of the formation, further improves this condition in practice.

Generally I prefer to use long-fiber sulphite paper stock, no adhesive being used between the folded portions. The thickness of the stock depends upon the form and capacity of the container, the number of plies used, and the quality of the paper stock. For sulphite paper stock used for containers with tapering side walls of one-pint capacity, thirty-point thickness for single-ply stock and fifteen-point thickness for two-ply stock are satisfactory. The proper thickness of the cap and the bottom member depends upon their diameter, and the material with which the container is to be filled, a thickness of about sixty-point stock being satisfactory for a single-ply cap, about thirty-point stock for a single-ply bottom member and about fifteen-point stock for a two-ply bottom member, in a container of one-pint capacity and of substantially the proportions illustrated in Fig. 1, when used for liquids.

Containers herein disclosed are suitable for transporting and storing liquids, as milk, molasses, etc., or solids, as butter, lard, etc. In certain cases, the finished containers are paraffined to render them completely waterproof. Whether or not they are paraffined, they are comparatively strong and durable particularly at the neck and bottom, and they retain their gage dimensions and hermetical closures almost permanently both before and after filling.

Having thus described my invention, what I claim is:

1. In a paper container, a side wall, and a highly-compressed practically-solidified 5 multi-reenforced neck therefor formed from a continuation of the stock thereof folded into three overlying rigidly-set portions in intimate surface contact with one another.
2. In a paper container, a side wall, and a 10 highly-compressed practically-solidified multi-reenforced neck therefor formed from a continuation of the stock thereof folded into three overlying rigidly-set portions in intimate surface contact with one another, the 15 neck merging into the inside and outside surfaces of the side wall.
3. In a paper container, a side wall, and a highly-compressed practically-solidified multi-reenforced neck therefor formed from a 20 continuation of the stock thereof folded into three overlying rigidly-set portions in intimate surface contact with one another, the meeting edges of the side wall and the folded portion of the neck being in intimate 25 surface contact.
4. In a paper container, a side wall, and a highly-compressed practically-solidified multi-reenforced neck therefor formed from a 30 continuation of the stock thereof folded into three overlying rigidly-set portions in intimate surface contact with one another, the neck having a flat periphery.
5. In a paper container, a side wall, and a 35 highly-compressed practically-solidified multi-reenforced neck therefor formed from a continuation of the stock thereof folded into three overlying rigidly-set portions in intimate surface contact with one another, the neck merging into the inside and outside 40 surfaces of the side wall and having a flat periphery.
6. In a paper container, a side wall, and a highly-compressed practically-solidified multi-reenforced neck therefor formed from a 45 continuation of the stock thereof and comprising a base portion, a reversely-extending intermediate portion, and an enclosed terminal portion rigidly set in intimate surface contact with said base and intermediate portions.
7. In a paper container, a side wall, and a 55 highly-compressed practically-solidified multi-reenforced neck therefor formed from a continuation of the stock thereof and comprising a base portion, a reversely-extending intermediate portion, and an enclosed terminal portion rigidly set in intimate surface contact with said base and intermediate portions, the joining section of said base and 60 intermediate portions lying flat over the periphery of said terminal portion to form a flat periphery for the container.
8. In a paper container, a side wall, and a 65 highly-compressed practically-solidified multi-reenforced neck therefor formed from a 70 continuation of the stock thereof and comprising a base portion, a reversely-extending intermediate portion, and an enclosed terminal portion rigidly set in intimate surface contact therewith.
9. In a paper container, a side wall, and a 75 highly-compressed practically-solidified multi-reenforced neck therefor formed from a continuation of the stock thereof and comprising a base portion, a reversely-extending intermediate portion, and an enclosed terminal portion rigidly set in intimate surface contact with said base and intermediate portions, the joining section of said intermediate and terminal portions lying in uninterrupted 80 conformity with a surface of the side wall.
10. In a paper container, a side wall, and a highly-compressed practically-solidified multi-reenforced neck therefor formed from a 85 continuation of the stock thereof and comprising a base portion, a reversely-extending intermediate portion, and an enclosed terminal portion rigidly set in intimate surface contact with said base and intermediate portions, the joining section of said intermediate and terminal portions lying in uninterrupted conformity with a surface of the side wall and being rigidly set in intimate 90 surface contact therewith.
11. In a paper container having a side wall, a multi-reenforced neck therefor formed from a continuation of the stock thereof and comprising a base portion, a reversely-extending intermediate portion, and an enclosed terminal portion consolidated with said base and intermediate portions, the joining section of said base and intermediate portions lying flat over the periphery of said terminal portion rigidly 100 set in intimate surface contact therewith, and the joining section of said intermediate and terminal portions lying in uninterrupted conformity with a surface of the side wall and being rigidly set in intimate surface contact therewith.
12. In a paper container, a side wall, and a highly-compressed practically-solidified multi-reenforced neck therefor formed from a 105 continuation of the stock thereof folded into three overlying rigidly-set portions in intimate surface contact with one another and having a cap-retaining groove.
13. In a paper container, a side wall, and a highly-compressed practically-solidified multi-reenforced neck therefor formed from a 110 continuation of the stock thereof folded into three overlying rigidly-set portions in intimate surface contact with one another, the neck having a cap-retaining groove and being flared outwardly above the groove.

14. In a paper container, a side wall, and a highly-compressed practically-solidified multi-reenforced neck therefor formed from a continuation of the stock thereof folded into three overlying rigidly-set portions in intimate surface contact with one another, the neck having a cap-retaining groove with its upper peripheral edge outside its lower peripheral edge.
- 10 15. In a paper container, a side wall, and a highly-compressed practically-solidified multi-reenforced neck therefor formed from a continuation of the stock thereof folded into three overlying rigidly-set portions in 15 intimate surface contact with one another, the neck having a cap-retaining groove bounded below by a section in uninterrupted conformity with the side wall and bounded above by a section flaring outwardly.
- 20 16. In a paper container, a side wall, and a highly-compressed practically-solidified multi-reenforced neck therefor formed from a continuation of the stock thereof and comprising a base portion, a reversely-extending 25 intermediate portion, and an enclosed terminal portion rigidly set in intimate surface contact with said base and intermediate portions, the neck having a cap-retaining groove.
- 30 17. In a paper container, a side wall, and a highly-compressed practically-solidified multi-reenforced neck therefor formed from a continuation of the stock thereof and comprising a base portion, a reversely-extending intermediate portion, and an enclosed terminal 35 portion rigidly set in intimate surface contact with said base and intermediate portions, the neck having a cap-retaining groove with its upper peripheral edge outside its lower peripheral edge.
- 40 18. In a paper container, a side wall, and a highly-compressed practically-solidified multi-reenforced neck therefor formed from a continuation of the stock thereof and comprising a base portion, a reversely-extending intermediate portion, and an enclosed terminal 45 portion rigidly set in intimate surface contact with said base and intermediate portions, the neck having a cap-retaining groove and being flared outwardly.
- 50 19. In a paper container, a side wall, and a highly-compressed practically-solidified multi-reenforced neck therefor formed from a continuation of the stock thereof and comprising a base portion, a reversely-extending intermediate portion, and an enclosed terminal 55 portion rigidly set in intimate surface contact with said base and intermediate portions, the neck having a cap-retaining groove bounded below by a section in uninterrupted 60 conformity with the side wall and bounded above by a section flaring outwardly.
- 65 20. In a paper container, a tapering side wall, and a reenforced neck therefor formed from folded portions of a continuation of the stock thereof and having a cap-retaining
- groove bounded below by a section of said folds in uninterrupted conformity with the taper of the side wall and bounded above by a section having an increased taper.
21. In a paper container, a tapering side wall, and a reenforced neck therefor formed from folded portions of a continuation of the stock thereof and having a cap-retaining groove bounded below by a section of said folds conforming to the taper of the side wall and bounded above by a section having an increased taper, the upper peripheral edge of the groove lying outside its lower peripheral edge.
22. In a paper container, a side wall of non-calendered stock, and a reenforced neck for the container formed from a continuation of the stock thereof and composed of a plurality of folds highly compressed to form the same into a practically integral mass.
23. In a paper container, a side wall of non-calendered stock, and a three-ply neck for the container formed from a continuation of the stock of the side wall folded double on itself and having the contacting surfaces thereof united by high compression.
24. In a paper container, a side wall of non-calendered stock, and a reenforced neck for the container formed from a continuation of the stock of the side wall and comprising a base portion, a reversely-extending intermediate portion, and an enclosed terminal portion consolidated with said base and intermediate portions.
25. In a paper container, a side wall of multiple-ply stock incorporating a binder, and a reenforced neck for the container formed from a continuation of the stock of the side wall into a series of folds, the contacting surfaces of which are united by high compression.
26. In a paper container, a side wall of multiple-ply stock incorporating a binder, a multi-reenforced neck therefor formed from a continuation of the stock of the side wall and comprising a base portion, a reversely-extending intermediate portion, and an enclosed terminal portion consolidated with said base and intermediate portions.
27. In a paper container, a side wall, and a highly-compressed practically-solidified hermetically-sealed closure therefor comprising a paper member having a turned-over base portion with a reversely-extending terminal portion of abbreviated length, and a side wall continuing portion on the inside and outside surfaces of said base and terminal portions in intimate surface contact therewith.
28. In a paper container, a side wall, and a highly-compressed practically-solidified hermetically-sealed closure therefor comprising a paper member having a turned-over base portion with a reversely-extending

- terminal portion of abbreviated length, and a side wall continuing portion on the inside and outside surfaces of said base and terminal portions in intimate surface contact therewith, the closure having a flat outer periphery.
29. In a paper container, a side wall, and a highly-compressed practically-solidified hermetically-sealed closure therefor comprising a paper member having a turned-over base portion with a reversely-extending terminal portion of abbreviated length, and a side wall continuing portion on the inside and outside surfaces of said base and terminal portions in intimate surface contact therewith, the closure having a flat inner periphery supporting said member and a flat outer periphery.
- 10 30. In a paper container, a side wall, and a highly-compressed practically-solidified hermetically-sealed closure therefor comprising a paper member having a turned-over base portion with a reversely-extending terminal portion of abbreviated length, and a side wall continuing portion on the inside and outside surfaces of said base and terminal portions in intimate surface contact therewith, the closure having a flat outer periphery of a width totaling a double thickness of the member plus a triple thickness of the side wall continuing portion.
- 15 30. In a paper container, a side wall, and a highly-compressed practically-solidified hermetically-sealed closure therefor comprising a paper member having a turned-over base portion with a reversely-extending terminal portion of abbreviated length, and a side wall continuing portion on the inside and outside surfaces of said base and terminal portions in intimate surface contact therewith, the closure having a flat inner periphery supporting said member.
- 20 31. In a paper container, a side wall, and a highly-compressed practically-solidified hermetically-sealed closure therefor comprising a paper member having a turn-over base portion with a reversely-extending terminal portion of abbreviated length, and a side wall continuing portion on the inside and outside surfaces of said base and terminal portions in intimate surface contact therewith, the closure having a flat inner periphery supporting said member in intimate surface contact therewith.
- 25 32. In a paper container, a side wall, and a highly-compressed practically-solidified hermetically-sealed closure therefor comprising a paper member having a turned-over base portion with a reversely-extending terminal portion of abbreviated length, and a side wall continuing portion on the inside and outside surfaces of said base and terminal portions in intimate surface contact therewith, the closure having an intermediate ledge folded above the periphery of said terminal portion.
- 30 33. In a paper container, a side wall, and a highly-compressed practically-solidified hermetically-sealed closure therefor comprising a paper member having a turned-over base portion with a reversely-extending terminal portion of abbreviated length, and a side wall continuing portion on the inside and outside surfaces of said base and terminal portions in intimate surface contact therewith, the closure having an intermediate ledge folded above the periphery of said terminal portion.
- 35 34. In a paper container, a side wall, and a highly-compressed practically-solidified hermetically-sealed closure therefor comprising a paper member having a turned-over base portion with a reversely-extending terminal portion of abbreviated length, and a side wall continuing portion on the inside and outside surfaces of said base and terminal portions in intimate surface contact therewith, the closure having a flat inner periphery supporting said member and a flat outer periphery.
- 40 35. In a paper container, a side wall, and a highly-compressed practically-solidified hermetically-sealed closure therefor comprising a paper member having a turned-over base portion with a reversely-extending terminal portion of abbreviated length, and a side wall continuing portion on the inside and outside surfaces of said base and terminal portions in intimate surface contact therewith, the closure having a flat outer periphery of a width totaling a double thickness of said member plus a triple thickness of the side wall continuing portion, a flat inner periphery supporting said member, and an intermediate ledge above the periphery of said terminal portion.
- 45 36. In a paper container, a side wall of non-calendered stock, and a hermetically-sealed closure therefor comprising a paper member of non-calendered stock having a turned-over portion folded with a continuing portion of the side wall, and having the contacting surfaces thereof united by high compression.
- 50 37. In a paper container, a side wall of non-calendered stock, and a hermetically-sealed closure therefor comprising a paper member of non-calendered stock having a turned-over portion consolidated with a continuing portion of the side wall, the closure having a flat inner periphery supporting said member in consolidation therewith.
- 55 38. In a paper container, a side wall of non-calendered stock, and a hermetically-sealed closure therefor comprising a paper member of non-calendered stock having a turned-over portion and a reversely extended terminal portion consolidated with a continuing portion of the side wall, the closure having an intermediate ledge folded above the periphery of said terminal portion in consolidation therewith.
- 60 39. In a paper container, a side wall of non-calendered stock, and a hermetically-sealed closure therefor comprising a paper member of non-calendered stock having a turned-over portion and a reversely extended terminal portion consolidated with a continuing portion of the side wall, the closure having a flat inner periphery supporting said member in consolidation therewith and
- 70 75 80 85 90 95 100 105 110 115 120 125 130

having an intermediate ledge folded above the periphery of said terminal portion in consolidation therewith.

40. In a paper container, a side wall of 5 multiple-ply stock incorporating a binder, and a hermetically-sealed closure therefor comprising a paper member having a turned-over base portion with a reversely-extending terminal portion of abbreviated length, and 10 a side wall continuing portion on the inside and outside surfaces of said base and terminal portions.

41. In a paper container, a side wall, a bottom member therefor, a hermetically-sealed closure formed by folded portions of 15 the bottom member and a side wall continuing portion, a highly-compressed practically-solidified triple-enforced neck formed from a continuation of the side wall folded 20 into three overlying rigidly-set portions in intimate surface contact with one another and having a cap-retaining groove, and a removable cap retained in said groove.

42. In a paper container, a side wall, a bottom member therefor, a hermetically-sealed closure formed of folded portions of 25 the bottom member and a side wall continuing portion, a triple-enforced neck formed from a continuation of the side wall folded 30 into three overlying rigidly-set portions and having a cap-retaining groove, and a removable cap retained in said groove.

43. In a paper container, a side wall, a bottom member therefor, a hermetically-sealed closure formed of folded portions of 35 the bottom member and a side wall continuing portion, a highly-compressed practically-solidified triple-enforced neck formed from a continuation of the side wall folded into 40 three overlying rigidly-set portions in intimate surface contact with one another and having a cap-retaining groove, and a removable cap retained in said groove.

44. In a paper container, a tapering side wall, a bottom member therefor, a hermetically-sealed closure formed by folded portions of 45 the bottom member and a side wall continuing portion, a multi-reenforced neck having folded-over portions consolidated 50 with each other and having a cap-retaining groove, and a removable cap retained in said groove.

45. In a paper container, a tapering side wall, a bottom member therefor, a hermetically-sealed closure formed by a folded portion of 55 the bottom member and a side wall continuing portion, a multi-reenforced outwardly-flaring neck formed from a continuation of the side wall folded into three overlying rigidly-set portions and having a cap-retaining groove, and a removable cap retained in said groove.

46. In a paper container, a tapering side wall, a bottom member therefor, a hermeti-

cally-sealed closure formed by a folded portion of the bottom member and a side wall continuing portion, a multi-reenforced outwardly-flaring neck having folded portions consolidated with each other and having a cap-retaining groove, and a removable cap 65 retained in said groove.

47. In a paper container, a side wall of multiple-ply stock incorporating a binder and having non-calendered surfaces, a bottom member therefor of non-calendered 75 stock, a hermetically-sealed closure formed by a consolidated portion of the bottom member and a side wall continuing portion, a reinforced neck having folded-over portions, the contacting surfaces of which are united 80 by high compression, and having a cap-retaining groove, and a removable cap retained in said groove.

48. In a paper container having a side wall of multiple-ply stock incorporating a 85 binder and having non-calendered surfaces, a bottom member therefor of multiple-ply stock incorporating a binder and having non-calendered surfaces, a hermetically-sealed closure formed by a consolidated portion of the bottom member and a side wall continuing portion, a reinforced neck having folded-over portions, the contacting surfaces 90 of which are united by high compression, and having a cap-retaining groove, and a removable cap retained in said groove.

49. A paper container having the edge of its body portion folded inwardly and downwardly to form the lip of the container, and having a closure-receiving seat formed by folding the inner wall inwardly, downwardly and outwardly, the material of the folds being of sufficient thickness and inherent strength to preserve the form of the closure seat.

50. A paper container having the edge of its body portion folded inwardly and downwardly to form the lip of the container, and having a closure-receiving groove having a 100 portion formed by folding the inner wall inwardly, downwardly and outwardly, the material of the folds being of sufficient thickness and inherent strength to preserve the form of the closure seat.

51. A paper container having the edge of its body portion folded inwardly and downwardly to form the lip of the container, and having a closure-receiving seat formed by folding the inner wall inwardly, downwardly and outwardly, and the last-mentioned outwardly-folded portion having an extension folded upwardly within the fold of the lip, the material of the folds being of sufficient thickness and inherent strength to preserve the form of the closure seat.

In testimony whereof I affix my signature.

ARLINGTON MOORE.
